CIGARETTE EXTINGUISHER

Ralph E. van Norstrand, Suffield, Conn.

Application April 8, 1941, Serial No. 387,403

12 Claims. (Cl. 131—237)

This invention relates to extinguishing devices for cigarettes and the like, and has particular reference to extinguishing devices which are moved into extinguishing position by the operation of a heat responsive member adjacent the lighted end of a cigarette. One object of the invention is to provide an improved device of this general character in which the heat responsive member will shift an extinguishing hood both toward and from the cigarette so that the device automatically opens up after the cigarette has been extinguished. A further object is to provide a device of the automatically resetting type in which there will be a substantial dwell in the extinguishing position even after the cigarette has cooled to the point where the heat responsive member tends to return to inactive position. Other objects will appear from the following description and claims.

Referring to the drawings,

Fig. 1 is an enlarged detail plan of an ash tray provided with an extinguishing member constructed in accordance with the invention;

Fig. 2 is a side elevation thereof;

Fig. 3 is an enlarged section on line 3—3 of Fig. 1;

Fig. 4 is a perspective detail;

Fig. 5 is a detail plan of a portion of the apparatus;

Fig. 6 is a perspective detail;

Fig. 7 is a view corresponding to Fig. 3 but showing the parts in a different position;

Fig. 8 is a detail of a modification;

Fig. 9 is a detail of a second modification;

Fig. 10 is a section (much enlarged) of a modified form of extinguisher embodying the present invention, taken on line 10—10 of Fig. 12;

Fig. 11 is a similar view taken on line 11—11 of Fig. 12;

Fig. 12 is a plan view of the form of extinguisher shown in Figs. 10 and 11, partially broken away;

Fig. 13 is a section on line 13—13 of Fig. 12; and

Fig. 14 is a view similar to Fig. 10 but showing the parts in a different position of operation.

The ash tray 10 has a cigarette rest 11 attached thereto and having a portion extending inwardly of the tray. For reasons which will appear below, this rest is preferably curved to conform closely to the shape of the cigarette. On one side the rest is provided with ears 12 which support a pin 13 upon which is pivoted at 14 a hood member 15. This hood member can swing from the inactive position shown in full lines

in Fig. 2 to the extinguishing position shown in dotted lines in that figure. Attached to a downwardly extending bracket 16, preferably formed integral with the rest, is a helical coil 17 formed of a bi-metallic strip or ribbon. This coil extends closely adjacent the end of the rest and is exposed by a concave notch 18 formed therein. When a cigarette is laid on the rest no action will be produced until it has burned back sufficiently to heat up the coil 17. When this occurs its end 19, which extends along the side of the rest underneath the pin 13 (Fig. 5), will be raised by the tendency of the coil to twist under heat.

15 Were the end of the extinguisher 19 to be attached directly to the hood 15 the latter would be moved into its extinguishing position when the coil was heated and would move back again when the coil again cooled off. This operation, 20 however, would tend to produce a fluttering of the hood while in contact with the cigarette and would also require a very substantial movement of the end of the coil. In accordance with the present invention both of these objections are avoided by introducing a lost motion connection between the bi-metallic strip and the hood 15. For this purpose a separate member 20 is employed, best shown in Fig. 6. This member has a portion 12 coiled around the pin 13 to serve as 25 a bearing, and an underlying portion 22 to which the strip is connected. The portion 21 has lateral lugs 23 which extend into notches 24 cut in the bearing portions 14 of the hood. The relative position of the lugs and notches are such 30 that if the member 20 is rocked counterclockwise, as viewed in Fig. 3, the lugs 23 will contact the rear side of the notch and cause the hood member to be swung upwardly. As soon as the hood reaches a vertical position it swings over 35 and drops by gravity against the cigarette, the notch being carried ahead of the lugs as is best shown in Fig. 7.

It will be seen from a comparison of Figs. 3 and 7 that by this means the motion given to the hood 15 is much greater than that given to the driving member 20. This makes it possible to employ a very much simpler operating structure than if the heat responsive member had to go through the entire motion imparted to the hood. A similar action takes place on the reverse stroke, where after the lost motion is taken up the lugs 23 engage the member 15 and push it once more to a vertical position whence it falls over into the full line position of Fig. 2.

55 It was stated above that it was desirable to

have the rest 11 shaped to conform closely to the outline of the cigarette. This is for the reason that mere contact with a closely fitting body of metal such as the rest 11 will of itself in time put out the cigarette. The hood member 15 has a similar effect, but in spite of the lost motion connection will not stay in closed position long after the cigarette has burned back far enough to uncover the coil 17. The close conformation of the rest and the hood to the shape of the cigarette causes a sweating action which greatly speeds up the extinguishing process, making certain that the cigarette will be put out even with a comparatively short dwell of the hood in contact with it.

Various other forms of operating mechanism may be used. For instance a metal bellows 30 shown in Fig. 8 may be connected directly to the member 20 and filled with a rapidly expandable material. This has the advantage in some cases of producing a straight line action instead of a rotation as in the case of the coil; and of producing a very considerable amount of motion yielding a substantial degree of power. Another way in which the device may be operated is shown in Fig. 9. A tube 31 shaped like the Bourdon tube used in a steam gauge is attached to the bracket 16 and passes the notch 18, then turning back underneath the body of the rest. At that point it is connected by a link 32 with the member 20. The tube is filled with a rapidly expandable material; and when the latter is heated the tube tends to straighten, causing the operating member 20 to rotate around the pin and throw the hood into active extinguishing position.

It is not necessary that the hood be confined to a single member at one side which passes entirely over the top of the cigarette. As in Figs. 10 to 14 the hood member may be made in two sections 35 each pivoted at 36 beside the cigarette rest 37. A heat responsive member, here shown as a bellows 38 similar to the bellows 30, as secured at one end as to a bracket 39 at one side of the rest; and has at its other end a pin 40 bearing collars 41 positioned to engage an extension on one of the hoods 35. The hood members have interlocking sections 42, as shown in Figs. 12 and 13, so that they are forced to move simultaneously and in opposite directions. One of the members 35 is provided with a lug 43 (Fig. 11) over which and over a pin 44 on the bracket 39 is compressed a spring 45. This spring forms a toggle by which the hood members will be snapped past a dead center position into either open or closed relation, as is apparent from a comparison of Figs. 11 and 14. It is desirable to have the lost motion connection provided by the collars 41 in order to permit the spring to act quickly and to give an additional dwell to the hood members in closed position, as has been discussed above in connection with other forms of the invention.

What I claim is:

1. An extinguishing device for cigarettes and the like comprising a rest, at least one extinguishing member mounted for movement into and out of contact with a cigarette on said rest, a heat responsive member exposed to the lighted end of a cigarette on said rest, and a coupling between the extinguishing member and the heat responsive member to cause the extinguishing member to approach the rest as the heat responsive member is heated and to recede therefrom as the heat responsive member cools, said coupling including a lost motion connection.

2. An extinguishing device for cigarettes and

the like comprising a rest, at least one extinguishing member mounted for movement into and out of contact with a cigarette on said rest, a heat responsive member comprising a coil of bimetallic ribbon exposed to the lighted end of a cigarette on said rest, and a coupling between the extinguishing member and the heat responsive member to cause the extinguishing member to approach the rest as the heat responsive member is heated and to recede therefrom as the heat responsive member cools, said coupling including a lost motion connection.

3. An extinguishing device for cigarettes and the like comprising a rest, at least one extinguishing member mounted for movement into and out of contact with a cigarette on said rest, a heat responsive member comprising a bellows-like tube filled with an expandable substance, said tube being exposed to the lighted end of a cigarette on said rest, and a coupling between the extinguishing member and the heat responsive member to cause the extinguishing member to approach the rest as the heat responsive member is heated and to recede therefrom as the heat responsive member cools, said coupling including a lost motion connection.

4. An extinguishing device for cigarettes and the like comprising a rest, at least one hood pivoted adjacent the rest and movable from an inactive position to a position embracing the cigarette, a heat responsive member exposed to the lighted end of a cigarette on said rest, and a coupling between the hood and the heat responsive member to cause the heat responsive member to cause the hood to approach the rest as the heat responsive member is heated and to recede therefrom as the heat responsive member cools, said coupling including a lost motion connection.

5. An extinguishing device for cigarettes and the like comprising a rest, a hood member pivoted adjacent the rest and movable from an inactive position through a vertical position and thence to a position embracing the cigarette, a heat responsive member exposed to the lighted end of a cigarette on said rest and including a lost motion connection, whereby as the heat responsive member is heated by the lighted end of the cigarette it will move the hood past its vertical position to permit gravity to move it to the cigarette and as the heat responsive member cools it will move the hood past the vertical position in the opposite direction to permit gravity to move it to inactive position.

6. An extinguishing device for cigarettes and the like comprising a rest, a pivot adjacent the rest, a hood mounted on said pivot for swinging movement from an inactive position through a vertical position and thence to a position embracing the cigarette, a heat responsive member exposed to the lighted end of a cigarette on said rest, an operating member pivoted on said pivot and having a lost motion interfitting connection with said hood, and a connection between the heat responsive member and the operating member, whereby as the heat responsive member is heated by the lighted end of the cigarette it will move the hood past its vertical position to permit gravity to move it to the cigarette and as the heat responsive member cools it will move the hood past the vertical position in the opposite direction to permit gravity to move it to inactive position.

7. An extinguishing device for cigarettes and the like comprising a rest, a pivot adjacent the rest, a hood mounted on said pivot for swinging

movement from an inactive position through a vertical position and thence to a position embracing the cigarette, a heat responsive member comprising a coil of bimetallic ribbon exposed to the lighted end of a cigarette on said rest, an operating member pivoted on said pivot and having a lost motion interfitting connection with said hood, and a connection between the heat responsive member and the operating member, whereby as the heat responsive member is heated by the lighted end of the cigarette it will move the hood past its vertical position to permit gravity to move it to the cigarette and as the heat responsive member cools it will move the hood past the vertical position in the opposite direction to permit gravity to move it to inactive position.

8. An extinguishing device for cigarettes and the like comprising a rest, a pivot adjacent the rest, a hood mounted on said pivot for swinging movement from an inactive position through a vertical position and thence to a position embracing the cigarette, a heat responsive member comprising a bellows-like tube filled with an expansible substance, said tube being exposed to the lighted end of a cigarette on said rest, an operating member pivoted on said pivot and having a lost motion interfitting connection with said hood, and a connection between the heat responsive member and the operating member, whereby as the heat responsive member is heated by the lighted end of the cigarette it will move the hood past its vertical position to permit gravity to move it to the cigarette and as the heat responsive member cools it will move the hood past the vertical position in the opposite direction to permit gravity to move it to inactive position.

9. An extinguishing device for cigarettes and the like comprising a rest, at least one hood pivoted adjacent the rest, a toggle spring operative to force the hood into either inactive or cigarette embracing position, and heat responsive

means exposed to the lighted end of a cigarette on said rest and coupled with said hood to initiate its movement selectively toward both positions.

- 5 10. An extinguishing device for cigarettes and the like comprising a rest, at least one hood pivoted adjacent the rest, a toggle spring operative to force the hood into either inactive or cigarette embracing position, and heat responsive 10 means exposed to the lighted end of a cigarette on said rest and coupled with said hood with a lost motion connection to initiate its movement selectively toward both positions.
11. An extinguishing device for cigarettes and 15 the like comprising a rest, a pair of hood members each pivoted at one side of the rest, interfitting connections between the hood members to constrain them for simultaneous and opposite motion, a toggle spring engaging at least one 20 of the members to snap the members either into inactive or cigarette embracing position, and heat responsive means exposed to the lighted end of a cigarette on said rest and coupled with said hood members to initiate their movement towards the cigarette as the heat responsive member is heated and towards their inactive position as the heat responsive member is cooled.
- 25 12. An extinguishing device for cigarettes and the like comprising a rest, a pair of hood members each pivoted at one side of the rest, interfitting connections between the hood members to constrain them for simultaneous and opposite motion, a toggle spring engaging at least one 30 of the members to snap the members either into inactive or cigarette embracing position, and heat responsive means exposed to the lighted end of a cigarette on said rest and coupled with said hood members with a lost motion connection to initiate their movement towards the cigarette as the heat responsive member is heated and towards their inactive position as the heat responsive member is cooled.

RALPH E. VAN NORSTRAND.
